UNITED STATES PATENT OFFICE.

JOSEPH JAGGER, OF GLENHAM, NEW YORK.

LOOM.

SPECIFICATION forming part of Letters Patent No. 403,194, dated May 14, 1889.

Application filed March 31, 1886. Serial No. 197,315. (No model.)

To all whom it may concern:

Be it known that I, JOSEPH JAGGER, of Glenham, in the county of Dutchess and State of New York, have invented a new and Improved Loom, of which the following is a full, clear, and exact description.

The object of my invention is to provide a new and improved loom for weaving Brussels velours.

10 The invention consists of a section-wheel operated and locked from the main shaft and connected with cams and levers operating the healds, the jacquard, and the picking devices, and of a device for insuring regular measurement of each pattern woven.

15 The invention also consists of various parts and details and combinations of the same, as will be fully described hereinafter, and then pointed out in the claims.

20 Reference is to be had to the accompanying drawings, forming a part of this specification, in which similar letters of reference indicate corresponding parts in all the figures.

Figure 1 is a broken side elevation of a 25 loom, showing my improvement. Fig. 2 is a plan view of the same, partly broken away. Fig. 3 is a face view of a section-wheel. Fig. 4 is a sectional elevation of the same. Fig. 5 is a face view of a section-wheel having twelve 30 divisions. Fig. 6 is a sectional elevation of the same. Fig. 7 is a face view of the two fine chain-cams. Fig. 8 is a face view of the picking-cam. Fig. 9 is a face view of the comber-board cam. Fig. 10 is a face view of 35 the driving and locking wheel for the section-wheel. Fig. 11 is an edge view of the same, and Fig. 12 is a side view of the healds and their operating mechanism.

The frame A of the loom is provided with 40 a crank-shaft, B, which operates the lay and other parts of the loom in the usual manner.

On one end of the shaft B is attached a driving and locking wheel, C, provided with the projecting pin C' and having an annular 45 raised projection, C². On the shaft D, having its bearings on a frame, A', secured at one side of the main frame A, is mounted the section-wheel E, having eight, twelve, or more slots or recesses, E', in its rim, and having the 50 curved parts E² between the recesses E', as shown in Figs. 3 and 5. The section-wheel E

is provided with a hub, E³, on which are mounted the fine chain-cams F and F', which are fastened to the section-wheel E by the bolts E⁴, projecting from the section-wheel E 55 and passing through suitable apertures in the fine chain-cams F and F'.

The fine chain-cams F and F' are each provided with a cam-groove, F², in which is placed a friction-roller, G², mounted on a stud 60 attached to the lever G or G', said levers being fulcrumed at one end on a shaft, H, mounted in suitable bearings attached to the main frame A and to the frame A'. The other ends of the levers G and G' are connected to the healds I I' by means of the levers g g', connecting-rods g², links g³, and hooks g⁴ g⁵, as shown clearly in Fig. 12.

On the hub E³ of the section-wheel E are also placed the working-cams J J', also fastened to the section-wheel E by the bolts E⁴, which are passed through the working-cams. Each of the working-cams J J' is provided with a cam-groove, J², (shown in Fig. 8,) in which is placed a friction-roller, K², mounted 75 on a stud attached to the levers K and K', respectively, one end of each of said levers being fulcrumed on the shaft H. The other end of the lever K' is connected, by the link L, with an arm, L', secured to a shaft, L², 80 mounted in suitable bearings on the frames A and A', and the other end of the lever K is connected, by the link M, with an arm, M', attached to a sleeve, M², fitted on the shaft L².

On the shaft D is placed a cam, N, the periphery of which is in contact with a friction-wheel, N', mounted on a stud attached to a lever, N², one end of which is fulcrumed on the shaft H, while the other end is connected with and operates the jacquard, which produces the pattern or design, in the usual manner.

The shaft L² is provided with an upright arm, L³, operating the horizontal oscillating picking-shaft O on the left side of the frame 95 A, and the sleeve M² is provided with an upright arm, M³, operating the horizontal oscillating picking-shaft P on the right of the frame A. The picking-shafts O and P are operated by the action of the revolving comber-board cams Q, secured to the shaft D, and provided with one, two, three, or more pick-

ing-cams, Q', and the cams Q operate the levers R in the usual manner for working the Jacquard harness comber-board.

The spike or breast-roller S, which draws forward the carpet as it is woven, is operated by a worm and worm-wheel from the shaft D by the inclined shaft S', provided with the clutch S² and the clutch-lever S³, for stopping the rotation of the shaft S' for letting back the cloth. The shaft S' is provided on its upper end with a worm, S⁴, which is in gear with the worm-wheel S⁵, attached to the shaft S⁶, on which the breast-roller S is mounted. To the shaft S⁶ is attached, by means of a set-screw, the roller T, having on its periphery small projecting pegs T'.

On the cross-bar A³ of the main frame A is attached the guide-plate U, and over it and the roller T passes an endless belt, V, which also passes under a tension-roller, W, mounted in a suitable bearing attached to the floor. The belt V is provided with a number of apertures corresponding to the pegs T' on the roller T.

The operation is as follows: Each revolution of the crank-shaft B rotates the wheel C once, so that the pin C', projecting into the top recess, E', of the section-wheel E, turns the latter in the direction of the arrow a' the distance of the division of the section-wheel used—that is, an eighth or a twelfth part of the periphery of the said wheel E. As soon as the pin C' leaves the recess E' the section-wheel remains stationary until the pin C' comes in contact with the next recess E' of the section-wheel E, and the latter is held in a locked position during the stationary period by the annular projection C² being in close contact with the curved part E² of the section-wheel. This partial rotation of the section-wheel E is imparted to the fine chain-cams F and F' and to the working-cams J and J'. As the two fine chain-cams F and F' are placed in opposite positions to each other, as shown in Fig. 7, they operate the healds I and I' alternately, and as the two working-cams J and J' are also placed in opposite positions to each other they alternately operate the picking-shafts O and P. As the main crank-shaft B rotates eight or twelve times before imparting a full revolution to the section-wheel and the cams attached to it, it will be seen that the healds and the picking-shafts are operated correspondingly through the respective levers G G' and K K', provided with the friction-rollers K² and G², which engage with the respective cam-grooves and the several connections with the healds and the picking-shafts above described. The picking-shafts O and P are alternately placed in position for picking by the arm L³, attached to the shaft L², and the arm M³, attached to the sleeve M². When a section-wheel, E, having twelve divisions or slots, E', in its rim, as shown in Figs. 1 and 5, is employed, then the picking is accomplished by, first, left, right, left, then miss or stand for three revolutions

of the crank-shaft, making six revolutions of the crank-shaft, and then repeat, picking right, left, right, and miss or stand again 70 during three revolutions of the crank-shaft, making again six revolutions of the crank-shaft, thus making twelve revolutions of the crank-shaft to one revolution of the said section-wheel.

The shuttle ceases to operate whenever the rollers K² of the working-cams J J' are on a level, as the said rollers K² then travel on the depressed circular part of the groove of the cams J J', and the levers K K', operated by the said rollers K², remain inactive. The levers K K' are again raised and lowered alternately, when the said rollers K² travel over the irregular parts of the grooves of the cams J J'. As shown in Fig. 8, the rollers are one 85 above the other and the shuttle is operating.

At the stopping of the shuttle the pile wire for the loop is drawn out of the cloth and placed under the warp raised by the jacquard. Now, when a section-wheel, E, having eight 90 divisions or slots, E', in its rim, as shown in Fig. 3, is employed, then the picking is accomplished by first left, right, left, miss or stand for one revolution of the crank-shaft, making four revolutions of the crank-shaft, 95 and one half-revolution of the section-wheel, and then right, left, right, miss or stand for one revolution of the crank-shaft, making again four revolutions of the crank-shaft and one half-revolution of the section-wheel. 100 Thus the crank-shaft makes eight revolutions to one full revolution of the section-wheel, having eight slots, E'.

The revolving of the shaft D imparts a rotary motion to the spike or breast-roller S by 105 means of the shaft S' and worm S⁴ and the worm-wheel S⁵, attached to the shaft S⁶, and as the roller T is attached to the latter the belt V travels with the same speed as the woven fabric which passes over the roller S. 110

The object of the belt V is to insure regular measurement of each pattern woven, and if the latter is, for instance, sixty inches long the belt is to made of the same length. The belt V does not change its relative length by 115 traveling around the roller T and the friction-roller W, being propelled by the pegs T' engaging with the corresponding apertures in the belt; but the worsted or woolen printed warp does vary its length as the fabric is 120 woven, and has to be regulated by the dead-weight on the tension device usually employed on the warp.

The dead-weight on the tension device is increased or diminished according to the variation in the length of the patterns in the warp as the weaving progresses. If this variation in the length of the pattern in the warp were not regulated, then the weft would not be united with the warp at the proper point, and 130 the pattern of the finished carpet would be distorted.

By increasing or diminishing the dead-weight on the tension device while the weav-

ing is progressing the warp is stretched or relaxed, so that the weft enters at the proper point, thus forming the correct and uniform pattern on the finished carpet. Now, it is evident that as the fabric and the belt V travel together the variation in the length of the pattern of the fabric can be at once discovered by referring to a starting-mark on the belt, and the weaver can increase or diminish the dead-weight on the tension device, so as to correct the difference of travel of the belt and the fabric.

Having thus fully described my invention, I claim as new and desire to secure by Letters Patent—

1. The combination of the crank-shaft B, the driving and locking wheel C, and the section-wheel E, with the fine chain-cams F and F', the levers G and G', provided with the friction-rollers G², the healds and intermediate devices between the healds and levers, substantially as shown and described.

2. The combination of the crank-shaft B, the driving and locking wheel C, and the section-wheel E, with the working-cams J and J', the levers K and K', provided with the friction-rollers K², the picking-shafts O and P, and intermediate mechanism between the said shafts and levers, substantially as shown and described.

3. The combination of the section-wheel E, the driving and locking wheel C, the crank-shaft B, and the working-cams J and J', having cam-grooves J², with the shafts O P, the levers K and K', having the friction-rollers 35 K², the connecting-links L and M, the arms L' and M', the shaft L², having the arm L³, and the sleeve M², having the arm M³, substantially as herein shown and described.

4. The combination of the working-cams J 40 and J', having cam-grooves J², the levers K and K', provided with friction-rollers K², the links L and M, and the arms L' and M', with the shaft L², provided with the arm L³, the picking-shaft O, the sleeve M², provided with 45 the arm M³, and the picking-shaft P, substantially as shown and described.

5. The combination, with the shaft D, the shaft S⁶, the breast-roller S, and means for operating the shaft S⁶ from the shaft D, of the 50 roller T, provided with the pegs T', and the endless belt V, substantially as herein shown and described.

JOSEPH JAGGER.
